(57) **CLAIM**

The ornamental design for a file cabinet, as shown and described.

DESCRIPTION

FIG. 1 is a front perspective view of a file cabinet, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is an enlarged detail view of area 17 in FIG. 1;

FIG. 18 is an enlarged detail view of area 18 in FIG. 2; and, FIG. 19 is an enlarged detail view of area 19 in FIG. 7.

The small evenly spaced dashed broken lines in the drawings illustrate portions of the file cabinet that form no part of the claimed design. The dot-dash broken lines encircling portions of the file cabinet in FIGS. 1, 2, and 7 and illustrated in enlarged views in FIGS. 17-19 form no part of the claimed design.

1 Claim, 19 Drawing Sheets
